INVENTOR,

Soyall J. Miller

ATTORNEY

UNITED STATES PATENT OFFICE

2,440,582

BUILDING BLOCK FORM

Thomas L. Green, Oklahoma City, Okla.

Application May 31, 1946, Serial No. 673,328

1 Claim. (Cl. 25—119)

1

My invention relates to the art of making or molding building blocks or units, particularly those of concrete or other fluid or plastic substance capable of becoming hardened when sufficiently set or cured.

The prime object of the invention is to provide a building unit mold which will simultaneously form one or more pairs of complementary units, said units having meeting shoulders which will interlock and prevent relative displacement of the two units solely by virtue of their own weight.

Another object is to provide a mold of this class which is capable of embodiment for use in practically any usual or present day block-forming equipment.

A further object is to provide a mold for the purpose set forth, in which the portion which forms the interlocking shoulders may be made in various configurations and various angles of disposition.

Other objects will be apparent from the following description when taken in conjunction with the accompanying single sheet of drawings, wherein:

Figure 1 is a perspective view, partially in section, of a mold which utilizes a type of block separator made in accordance with the present invention; and

Figure 2 is an exploded perspective view showing two complete separated blocks and the separator which formed their adjacent and interlockable faces.

Like characters of reference designate like parts in both of the figures.

In the drawings:

The reference numeral 1 indicates, as a whole, an open topped mold or box which may be made of any suitable rigid material. The mold 1, as shown in the drawings, is made up of a flat rectangular bottom or floor 2, vertical parallel side walls 3 and 4, and vertical end walls 5 and 6. In the embodiment shown, the walls are illustrated as being integrally joined at the corners of the mold, and the whole seated removably around the floor 2, however, one or more of the walls could well be formed separate from the others, and possibly hinged to the floor or to another wall or walls.

The present embodiment of the mold further includes a pair of substantially cubical cores 7 and 8 which are either seated upon or made integral with the floor 2, and which reside within the confines of the four walls of the mold. The cores or core-forms 7 and 8 are spaced from each other, and are also spaced from the walls of the

2

mold 1 so as to provide space therearound for receiving suitable block-forming material, not shown.

The block-forming material may be of any suitable nature or consistency, so long as it is capable of being poured, flowed, tamped or pressed into the mold cavities, and so long as it is thereafter capable of setting or hardening into weight bearing blocks.

10 The mold, thus far described, may be entirely or partially conventional, and may be of the individual type, may be mounted in "gangs" or series, or may be the mold of a conventional block forming machine.

15 In carrying out the invention, a separator, partition, or divider 9 is provided for so dividing or separating the mold cavities that two blocks may be simultaneously formed, and for so shaping the adjacent faces of the two blocks, that they will contiguously interlock with each other when properly laid in a building wall.

For the particular mold shown in the drawings, the separator 9 is formed of a horizontal bar 10 to which are welded or otherwise rigidly attached 25 the upper ends of three spaced identical vertically disposed space dividing septa 12, 13 and 14.

The septa 12, 13 and 14 each comprises a lower vertical portion 15, an upper vertical portion 16 which is off-set laterally from the portion 15, and a laterally extending portion 17 which integrally connects the two vertical portions 15 and 16. The portion 17 is not horizontal, but instead, lies at an angle which is less than ninety degrees with relation to both of the vertical portions.

35 The elements 12, 13 and 14 are so spaced along the bar 10 that when the separator 9 is placed in the mold as shown in Fig. 1, the septum 14 resides in the space between the core 7 and the end wall 5, and an element similarly resides in the space 40 between the core 8 and the end wall 6, with the septum 13 standing in the space between the two cores.

The separator 9 is retained in such standing position by notches 18 in the floor 2, which receive the lower ends of the septa 12, 13 and 14, and notches in the upper ends of the end walls 5 and 6 which receive the outwardly projecting ends of the bar 10.

In Fig. 2 are shown two building blocks of a configuration which is formed by filling the mold cavities with suitable material, after the separator or spacer 9 has been installed therein, as shown in Fig. 1. The two blocks are indicated by the reference numerals 20 and 21.

55 In this instance, the block 20 consists of an

upright wall 22 having three identical laterally projecting webs or cross-walls 23, 24 and 25. Each web has an upwardly facing shoulder 26 which slants upwardly to the outer edge 27 of the web.

Similarly, but not identically, the block 21 has a vertical wall 28 with three identical laterally projecting webs 30, 31 and 32. The webs each have a downwardly facing shoulder 33 which is complementary to one of the upwardly facing shoulders 26 of the block 20.

In the present embodiment, the surfaces of the shoulders 26 and 33 are shown as being formed of reverse curves, but they could well be straight, stepped or notched, in fact they could be made in any configuration which would permit interlocking engagement between them, should the two blocks be laid in a wall with the shoulder surfaces meeting. In other words, the shoulder surfaces can be formed in any manner which will prevent separation of the blocks by virtue of their own weight or of any weight supported thereon, when the shoulders are inter-engaged.

It is pointed out that the separator 9 shown in the drawings is designed for use only in a mold for forming cell-type blocks, and that when non-cellular and non-web blocks are to be formed, the separator may be made of one piece or sheet which provides continuous block forming surfaces.

It is anticipated that blocks made by the present forming apparatus may be laid with a dividing layer of water-proofing material impinged between their interlocking surfaces 26 and 33, and that in some instances the layers may overlap at their edges. In such instances, the interlocking surfaces of the blocks may require off-set space for compensating for the over-lapped edge portions of the layers. To this end, it is contemplated that the separator may be off-set to provide such required space between the blocks.

While the embodiment of the invention shown in the drawings and described herein discloses a mold in which a pair of blocks are simultaneously formed while their interlocking transverse shoulders 26 and 33 are facing each other, the mold and separator could also be arranged in such a manner that when the blocks are being formed, the shoulders of both blocks face upwardly. The mold and separators could also be arranged so that the shoulders of the two blocks face outwardly from each other, or so that the blocks lie end to end with shoulders in alignment with each other.

In some instances the separator can be used as a part of the forming machine or equipment, so

that a single block can be formed in each compartment of the machine.

It is pointed out that the complementary blocks do not have to be of the same lateral dimension or thickness in order for them to function properly in a wall. It is therefore contemplated to in some instances so position the separator in the mold that it does not lie an equal distance from the two side walls 3 and 4.

In some types of block forming molds or machines, the operation may be such that it would be desirable to so mount the septa 12, 13 and 14 that they can be removed from the machine with one left in each web or cross-wall of the blocks until the blocks have taken their initial set.

It is pointed out that since the shoulders or shelves 20 and 33 are complementary to each other, the blocks 20 and 21 may be shifted longitudinally with relation to each other when laid in a wall without affecting the inter-locking seal between the blocks.

Obviously, many changes in shape and configuration of both the septa 12 and the mold 1, or other forming machine, could well be made without defeating the practicability of the device, and I therefore do not wish to be confined to the preferred embodiment shown in the drawings and described herein, further than I am limited by the scope of the appended claim.

I claim:

30. In apparatus for forming building blocks, the combination with a hollow open topped box having vertical walls and a closed bottom, a central upstanding core in said box supported on said bottom, said core spaced inwardly from said walls to form interconnected vertical channels for receiving block forming material, of a removable septum in at least two of said channels, each septum including: two vertically disposed straight portions laterally spaced and vertically staggered with relation to each other; and a laterally extending portion connecting the adjacent ends of said straight portions, said connecting portion being slanted to form an acute angle with relation to the straight portions.
